UNITED STATES PATENT OFFICE.

THOMAS S. ALLEN, OF MILWAUKEE, WISCONSIN, ASSIGNOR TO ALLIS-CHALMERS COMPANY, A CORPORATION OF NEW JERSEY.

COMMUTATOR CONSTRUCTION FOR DYNAMO-ELECTRIC MACHINES.

1,017,945.

Specification of Letters Patent.

Patented Feb. 20, 1912.

Application filed February 28, 1910. Serial No. 546,541.

To all whom it may concern:

Be it known that I, THOMAS S. ALLEN, a citizen of the United States, residing at Milwaukee, in the county of Milwaukee and 5 State of Wisconsin, have invented certain new and useful Improvements in Commutator Constructions for Dynamo-Electric Machines, of which the following is a full, clear, and exact specification.

10 This invention relates to dynamo-electric machines, and particularly to improvements in construction and means for cooling commutators of high speed machines, such as turbo generators.

15 It is a well known fact that the commutators of machines of high speed and of large current output must be made relatively small in diameter, and even though the commutator is given considerable length the 20 segments become hot due to the high brush friction and contact losses. In such machines considerable difficulty has been experienced in supporting the segments, particularly when the segments are long, in a 25 manner such that they will not buckle or be distorted and shifted from position by expansion or by centrifugal force, and it has also been difficult to cool the commutator in a satisfactory manner and prevent a rise in 30 temperature which would affect the efficiency and operation of the commutator and brushes.

The object of the invention is to improve 35 the ventilation of commutators and to secure a better cooling effect than has been possible heretofore, and to support the segments in a manner such that there is no danger of the segments being displaced and so that a good circulation of air can take place through 40 the interior of the commutator and along the entire inner surfaces of the segments.

In carrying out my invention I provide 45 segment clamping and supporting means which engages the outer surfaces of the segments only, so that the entire inner surface of each segment is exposed to air currents which may be forced through the interior of the commutator. This is preferably accomplished by means of clamping rings 50 which are arranged tightly about the segments and which hold them securely in assembled relation in the form of an annulus or shell, the inward displacement of the segments being, of course, impossible because of 55 the tapered or wedge shaped construction

of the segments. The annulus is preferably supported concentrically with respect to the shaft of the machine by supporting devices which extend between the shaft and two of the clamping rings near the ends of the segments, these supporting devices being preferably in the form of disks which are mounted upon the shaft, and are provided with openings through which air may pass freely to and from the commutator. Air may be 60 caused to circulate or pass through the commutator by any suitable fan or blower, which, according to the present invention is mounted on the shaft near the outer end of the commutator. 70

The invention may be further briefly summarized as consisting in certain novel details of construction and combinations and arrangements of parts which will be described in the specification and set forth in the ap- 75 pended claims.

Reference is had to the accompanying sheet of drawings, in which—

Figure 1 is a partial elevation and partial longitudinal sectional view of part of an armature of a dynamo-electric machine and of a commutator constructed in accordance with my invention; Fig. 2 is a sectional view substantially along the line 2—2 of Fig. 1 looking in the direction indicated by the arrow, part of the blading of the fan or blower being removed; Fig. 3 is a plan view of a portion of one of the split segment-clamping rings; and Fig. 4 is an enlarged 80 85 90 sectional view through a portion of the blad- ing of the blower.

Referring now to the figures of the drawings, 10 represents a portion of the armature, and 11 the shaft of a direct current dynamo-electric machine such as a turbo-generator or other direct current machine having a long commutator the segments of which are shown at 12.

Instead of clamping the segments onto seats or inner supporting devices, or of employing V-shaped clamping rings engaging undercut slots in the ends or inner surfaces of the segments, as is the present common practice, I leave the segments unsupported on the interior and hold them in assembled 100 relation or in the form of an annulus or shell by clamping devices which surround the segments and engage the latter on the exterior only. In this case this is accomplished by means of several sets of clamp- 105 110

ing rings each set consisting of an inner tapered and adjustable ring 13 having its outer surface threaded and an outer ring 14 which is tapered and threaded on its inner surface and is screwed tightly upon the inner ring 13 so as to contract the inner ring and draw the segments tightly together. Each of the inner rings 13 is rendered adjustable by being split or by means of a diagonal slot 15 shown most clearly in Fig. 3. Three sets of rings are here shown, two sets being arranged near the ends of the commutator and one at the middle thereof. All the inner rings 13 are separated from the segments by suitable insulation 16, and the inner surfaces of the rings 13 of the two outer or end sets are each slightly tapered in opposite directions from the center as shown in Fig. 1, and engage within correspondingly tapered portions of the segments. This construction assures against endwise shifting of the segments relative to the clamping rings. It will be seen that the segments and rings form a unit and may be easily assembled remote from the machine and afterward secured on the shaft, or removed as a whole from the machine.

The annulus or shell of segments is supported concentrically with respect to the shaft, and in a manner such as to leave an annular space between the inner surfaces of the segments and the shaft, by means of two disks 17 which are mounted on the shaft and are secured by screws 18 to horizontally projecting annular flanges 19 on the outer clamping rings 14 of the sets of rings at the ends of the commutator. The disks may be keyed to the shaft and are held in proper position axially thereof by a shoulder 20 which is engaged by the inner disk 17 adjacent the armature, and by nuts 21 which engage a threaded portion 22 of the shaft and bear against the outer disk 17. Each of the disks 17 is provided with a number of 45 ventilating openings 23 which permit free circulation of air through the interior of the commutator.

Any suitable fan or blower may be utilized for forcing air through the interior of the commutator, but in this case, the blower is mounted on the shaft adjacent the outer end of the commutator and includes a series of inclined curved blades 24 which are quite similar to the blades of a turbine. These 55 blades have bases which are secured by a calking strip 25 in the slot of a base ring 26 which is keyed to the shaft, and have their outer ends secured to a shroud ring 27. The blades are surrounded by a cylindrical casing 28 which is secured to the face of the adjacent commutator supporting disk 17.

It will be seen that with the segment clamping and supporting means which I have provided, the segments will be clamped 65 and held securely in position against dis-

placement and at the same time an unobstructed annular passageway is formed between the shaft and the inner surfaces of the segments. When the machine is in operation a large volume of air is forced through the interior of the commutator sweeping along the entire inner surfaces of the segments in a manner such as to cool them most effectively. The direction of rotation of the machine is indicated by the long arrow in Fig. 4, and the direction in which the air is forced by the blades is indicated by the shorter arrows in Fig. 4 and by the arrows in Fig. 1. With this construction the commutator can be cooled very effectively, the life of the segments and brushes is rendered greater than in the machines at present employed, and the operation of the commutator and brushes will be satisfactory at all times providing brushes of suitable capacity are employed.

I do not desire to be confined to the exact details shown, but aim in my claims to cover all modifications which do not involve a departure from the spirit and scope of my invention.

What I claim as new and desire to secure by Letters Patent is:—

1. In a commutator construction, a shaft, a plurality of segments surrounding said shaft, segment clamping and supporting means engaging the outer surfaces of the segments only, and means carried by the shaft for creating a flow of air between said segments and shaft. 100

2. In combination, a shaft, a commutator comprising segments in the form of an annulus, the segments being clamped together and held in assembled relation on the exterior only, means for supporting the annulus concentrically with respect to the shaft so as to leave an unobstructed air space between the inner surface of each segment and the shaft, and means on said shaft for forcing air through the interior of the commutator. 110

3. In a dynamo-electric machine, a shaft, a commutator comprising a plurality of segments arranged in the form of an annulus or shell, said segments being clamped together and held in assembled relation from the exterior only, and being supported from the shaft so as to leave an unobstructed annular passageway between the segments and the shaft, and means mounted on said shaft for creating a flow of air through said annular passageway. 120

4. In combination, in a dynamo-electric machine, a shaft, a commutator comprising an annulus or shell of segments, clamping rings engaging the outer surfaces of the segments and holding the latter in assembled relation, means mounted on the shaft for holding the annulus of assembled segments concentrically with respect to the shaft so as to leave an unobstructed passageway be- 130

tween the segments and the shaft, and means for causing a circulation of air through said passageway.

5. In combination, in a dynamo-electric machine, a shaft, a commutator comprising an annulus or shell of commutator segments, clamping rings engaging the outer surfaces of the segments only and holding the latter in assembled relation, means extending between said rings and shaft and beyond the ends of the segments for holding the annulus concentrically with respect to the shaft so as to leave unobstructed space between the shaft and the segments, and a blower for forcing air through said passageway along the inner surfaces of the segments throughout their length.

6. In combination, in a dynamo-electric machine, a shaft, a commutator comprising an annulus or shell of segments, clamping rings extending about the commutator for holding the segments in assembled relation, said segments being supported from the shafts so as to leave an unobstructed annular

passageway between the segments and the shaft, and a blower mounted on the shaft for forcing air through said passageway, said blower comprising blades secured to a plurality of rings.

7. In combination, in a dynamo-electric machine, a shaft, a commutator supported concentrically relative to said shaft so as to leave an unobstructed passageway between said shaft and commutator, a blower mounted on said shaft at one end of said commutator for forcing air through said passageway, said blower comprising blades secured to rings at their extremities, and a casing surrounding said blades for directing the forced air.

Milwaukee, Wisconsin, February 16, 1910.

In testimony whereof I affix my signature, in the presence of two witnesses.

THOMAS S ALLEN.
